CLAIM

The ornamental design for a furniture arrangement, as shown and described.

DESCRIPTION

FIG. 1 is a front perspective view of a furniture arrangement embodying the present invention;

FIG. 2 is a side view of FIG. 1;

FIG. 3 is a rear view of FIG. 1; and,

FIG. 4 is a top view of FIG. 1.

The broken line showing of the chair glides is for illustrative purposes only and forms no part of the claimed design.
